UNITED STATES PATENT OFFICE.

JOHN A. CANFIELD, OF COLLINS, MISSISSIPPI, ASSIGNOR OF ONE-HALF TO MAC-Q COMPANY, INC., OF COLLINS, MISSISSIPPI.

POTATO CUTTER.

Application filed May 22, 1922. Serial No. 562,712.

To all whom it may concern:

Be it known that I, JOHN A. CANFIELD, a citizen of the United States, residing at Collins, in the county of Covington and State of Mississippi, have invented a new and useful Potato Cutter, of which the following is a specification.

This invention aims to provide novel means whereby sweet potatoes may be 10 formed into cylinders.

In the accompanying drawings:—

Figure 1 shows in side elevation, a device constructed in accordance with the invention; Figure 2 is a top plan; Figure 3 is a 15 longitudinal section taken on the line 3—3 of Figure 2; Figure 4 is a transverse section on the line 4—4 of Figure 3.

The mechanism for cutting the sweet potatoes into cylinders embodies a frame 21. 20 The frame 21 comprises cross bars 22 whereon cylindrical receivers 23 of different diameters are secured. Adjacent to their outer ends, the cylindrical receivers 23 are supplied with openings 24. A die 25 is mounted 25 in each receiver 23 and is provided with openings 26. The size of the openings 26 will depend upon the diameter of the cylinders into which the sweet potatoes are to be cut. Each die 25 has a flange 27 engaging 30 the end of the corresponding receiver 23. A retaining ring 28 is threaded on the receiver 23 and includes a flange 29, cooperating with the flange 27 of the die 25 to hold the die in place. The construction is such that one 35 die may be substituted for another readily should the die be broken or should it be desired to substitute, for any one die, another die having different sized openings 26.

Plungers 30 are mounted for reciprocation 40 in the receivers 23, each plunger comprising a pressure head 31, a guiding head 32 and a stem 33 connecting the heads. Pitmans 34 are pivoted at 35 to the parts 32 of the plungers 30 and are provided with straps 36 45 engaged with eccentrics 37 on a shaft 38 journaled on the frame 21 adjacent to the outer end thereof, the shaft 38 being supplied with any suitable means 50 whereby it may be rotated.

50 In practical operation, the pieces of sweet potato are placed by operators in the open-

ings 24 of the cylindrical receivers 23 between the dies 25 and the pressure heads 31 of the plungers 30. The shaft 38, the eccentrics 37, the straps 36 and the pitmans 34, impart reciprocating movement to the plungers 30, the plungers 30 sliding in the receivers 23. When the plungers are advanced, the pressure heads 31 crowd the potatoes through the openings 26 in the dies 25, the potatoes thus being cut up into cylinders or pencils.

The cylinders formed by the dies 25 pass upon a conveyor 40, operating beneath the projecting ends of the receivers 23. Stools 41 65 are disposed along the conveyor 40 and operators seated on the stools pick up the cylinders which have been formed in the dies 25, the cylinders ultimately being stood up endwise in cans, and packed for shipment. 70

Owing to the fact that each plunger 30 embodies spaced heads 32 and 31, and a stem 33 connecting the heads, any mashed potato which works to the right in Figure 3, between the head 31 and the wall of the receiver 23 may be removed readily, through the opening 24 when the head 31 is advanced toward the die 25, into the position shown in Figure 2, the thickness of the head 31 being less than the length of the opening 24. 80

What is claimed is:—

In a device of the class described, a frame, a receiver on the frame, a die carried by the receiver, the receiver being provided with an opening disposed adjacent to the die, a plunger mounted for reciprocation in the receiver, the plunger comprising a pressure head, a guiding head, and a reduced stem connecting the heads, the thickness of the pressure head being less than the length of the opening, 85 thereby to give access to the space between the head, when the plunger is advanced toward the die, and means for imparting reciprocation to the plunger.

In testimony that I claim the foregoing 90 as my own, I have hereto affixed my signature in the presence of two witnesses.

JOHN A. CANFIELD.
